RAZOR BLADE DISPENSER

George A. La Cas, Staunton, Va., assignor to Philip Morris Incorporated, New York, N.Y., a corporation of Virginia

Filed Apr. 4, 1961, Ser. No. 100,648
6 Claims. (Cl. 221—232)

This invention relates to devices for dispensing razor blades and the like, and especially for dispensing thin blades one-by-one. It is particularly adapted, for example, for embodiment in devices for the dispensing one-by-one of those slotted double-edge blades of extreme thinness which are commonly used in double-edge safety razors; and such devices may be of various types including those wherein a dispensed blade is deposited by hand in a razor and the type wherein the dispensed blade is injected directly into a razor.

It is important in such devices that only a single such blade be dispensed at a time, not only because of the inconvenience and shaving difficulties of the user when two blades are put into a razor at one time, but also because of the additional safety factor involved when there will be no occasion for the user to try to separate two blades which are ejected together.

In order to meet such considerations, devices having particularly balanced and/or proportioned parts have been provided, but devices of such types do not have as wide a field of adaptability as is often desirable, and are often expensive to manufacture. In addition, blades have been disposed in staggered relationship in a dispenser and dispensed from opposite sides thereof; but such an arrangement requires the use of an elongated dispenser, of a relatively complex dispenser construction, and, ordinarily, the elimination of the convenient slider for the dispensing of the blades.

It is also of importance that a razor-blade dispenser, being a disposable and quantity-production item, be as inexpensive to manufacture and assemble as is consistent with convenience and effectiveness of operation.

With the foregoing and other considerations in view, the present invention contemplates the provision of improved means for accurately and effectively assuring the ejection one-by-one of the stacked blades in a dispenser, and the provision of a convenient and economical dispenser construction.

In certain of its aspects, the invention contemplates the provision of a downwardly yieldable post normally extending thru the slots or other openings in all the blades of a stack, but depressed by a portion of a blade-ejecting slider to move to a position where it extends thru the openings of all but the topmost blade but is entirely below the opening in the topmost blade.

In other of its aspects, the invention contemplates the forming of a post of material cut out from and bent upwardly from the plates of resilient sheet material.

Other objects and features will be pointed out hereinafter.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention, reference should be had to the following detailed description taken in connection with the accompanying drawings, in which:

FIGURE 1 is a perspective view of one form of dispenser embodying the invention;

FIG. 2 is a view of the forward end thereof on an enlarged scale;

FIG. 3 is a top view, partly broken away;

2

FIG. 4 is a section on the line 4—4 of FIG. 3;
FIG. 4a is a perspective view of the slider;

FIG. 5 is a section on the line 5—5 of FIG. 3;

FIG. 6 is a plan view on a still larger scale of the structure embodying the post, the dot-and-dash lead lines thereon indicating portions from which the portions forming the post were cut away from the original blank;

FIG. 7 is a side view thereof;

FIG. 8 is a section on the line 8—8 of FIG. 7;

FIG. 9 is a greatly enlarged detail perspective view of the post;

FIG. 10 illustrates somewhat diagrammatically the starting point in a blade-ejecting operation;

FIG. 11 illustrates a later stage in the operation; and

FIG. 12 illustrates a still later stage therein.

In the exemplified embodiment of the invention there is provided a dispenser which is of the general type exemplified in the Butlin Patent 2,792,933, and which, as in that patent, comprises a magazine for a stack of blades and a slider for dispensing the topmost blade.

The body of the dispenser is provided, in the present instance, by an upper member 10 which may be formed of plastic and which provides a top 12 and forward and rearward walls 14 and 15, and a lower member 16 which may be formed of sheet metal and which provides a bottom 18. The sides of the dispenser are provided by upper side portions 20 on the upper member and carrying lugs 22, and a lower side portion formed by inwardly resilient portions 24 of the lower member and formed with longitudinal grooves 25 adapted to snap over and embrace the lugs 22.

The exemplified dispenser is separated into an upper dispensing magazine and a lower used-blade vault by a plate 26 having downwardly-extending supporting flanges 28 which rest on the bottom 18, and the bottom 18 is formed with a used-blade inlet slot 30.

A blade discharge slot 32 is formed at the forward upper end of the magazine, and a slider 34, movable in a slot 35 in the top 12, is provided for the ejection through the slot 32 of the topmost blade 36 of a stack 37 of double-edge blades, which may have a thickness of only six-thousandths of an inch (0.006") and which are formed with conventional slots 38 and solid portions 39 at each end. Cut out from the plate 26 are a pair of upwardly-resilient springs 40 and 41 which urge the blades of the stack toward the top 12. The slider carries at a rearward portion thereof dependent projections 42 of slightly less thickness than the thickness of a blade and providing forward shoulders 43 for engaging and dispensing the uppermost blade of a stack.

Pursuant to the present invention in certain of its aspects, in order to positively prevent the next-to-topmost blade of the stack from clinging to the topmost blade during the dispensing thereof or otherwise being dispensed with the topmost blade, there is provided toward the rear of the magazine an upwardly-spring-pressed downwardly-yieldable post 45 normally extending upwardly through the slots 39 of the blades of the stack, the spring 41 being cut out at 45a, in the present instance, to freely accommodate this post. On the lower edge of the slider, forwardly of the projection 41, and directly above the post when the slider is in its rearward position (FIG. 10), is a downward projection 46 having an effective portion above the post of greater thickness than the thickness of a single blade and of less thickness than the thickness of two blades. The distance between the projection 46 and the shoulders 43 should be sufficient to freely accommodate the rearward end portion 39 of the topmost blade, but not enough to permit the projection 46 to ride forwardly off the top of the post before said end portion 39 is above the same. When, therefore, the slider is moved forwardly, the shoulders 43 will engage the rear

60
65

end of the topmost blade and move it forwardly to positions above and then past the post 45. It will be noted that the space between projections 42 is greater than the thickness of the post, so that they will clear the post as the slider 34 is moved forwardly and rearwardly. Since 5 the post is spring-pressed upwardly, first against the projection 46, and later (as the slider moves forward) against the rear end of the topmost blade, and finally to a slightly but nevertheless higher position, the rear end of the next-to-topmost blade cannot move forwardly past the post. 10 It is to be observed that the projection 46 is no wider than the slot 32 in the blade, whereas the projections 42 are disposed over the blade on each side of the slot 32 and therefore hold the next-to-topmost blade down to a certain extent until the slider has substantially completed its 15 rearward movement after ejecting the topmost blade. When, however, the projection 46 reaches the post 45 during the rearward movement of the slider, the projection 46 cams the post downwardly under it, an inclined surface being provided on at least one of these members for that purpose. In the present instance, one is provided at 48 on the forward upper surface of the post and another at 49 on the rearwardly facing portion of the projection 46 on the slider. As, therefore, the projection 20 46 moves fully over the post 45 and the shoulders 43 move behind the end of the previously next-to-the-topmost and now topmost blade, this blade is ready for dispensing without the dispensing of the blade under it.

The present invention, moreover, in certain of its aspects, contemplates the provision of a particularly economical and effective construction of the post and its actuating spring. Below the plate 26 there is provided a normally-flat resilient sheet-metal plate 50 supported on the bottom 18 by side flanges 52 which fit inside the side flanges 28 on the plate 26. The plate 50 is unsupported otherwise, so that the longitudinal central portion thereof is downwardly yieldable. At each side of a rearward central portion 54 of the plate 50 there are cut out tabs 55 and 56 the inner sides of which are left attached to the central portion 54 on lines 57 and 58 respectively. The respective tabs 55 and 56 comprise narrow inner portions 59 and 60 and wider outer portions 61 and 62 each providing a wide piece 64 on one end and a narrow piece 65 on the other end. The outer surface of each tab is cut away on an inclined line 66 to the right (FIG. 6) of the portions 65. The post is formed by bending the tabs so that portions 59 and 60 thereof extend upwardly and inwardly and the portions 61 and 62 thereof extend upwardly, whereupon the tabs 64 are bent over each other at one end and the tabs 65 are bent over each other at the other end to provide the construction particularly shown in FIGS. 7 and 9. The inclined edges at 66 provide the inclined surface 48; and the post 45, which is integral with the plate 50, is resiliently mounted on this plate so that it can be pressed downwardly, bowing the plate 50 downwardly as the projection 46 presses against the surface 48 during the rearward movement of the slider, but so that it will be pushed upwardly in stages as the forward movement of the slider removes the projection 46 from above it, then removes the rear end of the blade from above it, and then removes the projection 42 from above it, the movement continuing until the plate 50 has returned to its normal position.

Details of construction not specifically referred to herein will be readily understood by reference to said Butlin Patent 2,792,933.

Since certain changes may be made in the above construction and different embodiments of the invention could be made without departing from the scope thereof, it is intended that all matter contained in the above description or shown in the accompanying drawings shall be interpreted as illustrative and not in a limiting sense.

The invention claimed is:

1. A blade dispenser comprising a receptacle containing a stack of thin blades having alined openings therein, means to urge said blades upwardly, a slot in the upper forward portion of said receptacle for dispensing a blade from said receptacle, a slider having blade-ejecting shoulder means and adapted for movement in a forward direction for dispensing thru said slot the uppermost blade in said stack and adapted for a return movement in a rearward direction, a downwardly-yieldable post within the receptacle and having a substantially horizontal upper surface at its rearward portion and a substantially vertical rearward surface meeting the same, and normally extending thru said openings of the blades in said stack but compressible to a position wherein said horizontal surface will lie below the uppermost blade of said stack and wherein said vertical surface will provide a positive stop in the path of forward movement of the next-to-uppermost blade of the stack, said slider having a downward projection with a rearwardly-facing portion therein disposed forwardly of said shoulder means and depending below said shoulder means and below the plane of said horizontal surface when said post extends thru said openings and said post having an upper forward portion in the path of rearward movement of the rearwardly-facing portion of said projection, and at least one of said rearwardly-facing portion of said slider and said upper forward portion of said post being formed with an upwardly and rearwardly inclined camming surface to engage the other of the last mentioned portions during the rearward movement of said slider to cam the post downwardly and permit the projection to ride over the post and to maintain the post depressed until the uppermost blade has been moved forwardly by said shoulder means at least sufficiently to bring the rear edge of the opening in the uppermost blade above said post.
2. A blade dispenser as in claim 1 wherein said camming surface is formed on said portion of said projection.
3. A blade dispenser as in claim 1 wherein said camming surface is formed on said portion of said post.
4. A blade dispenser as in claim 1, wherein said projection is of less lateral extent than the minimum lateral extents of said openings thru which said post extends.
5. A blade dispenser as in claim 4 wherein said blade-ejecting shoulder means comprises a pair of elements spaced from each other a distance greater than the thickness of said post and movable past said post at both sides thereof.
6. A blade dispenser comprising a receptacle containing a stack of thin blades having alined openings therein, means to urge said blades upwardly, a slot in the upper forward portion of said receptacle for dispensing a blade from said receptacle, a slider adapted for movement in a forward direction for dispensing thru said slot the uppermost blade in said stack and adapted for a return movement in a rearward direction, a plate of resilient material beneath said blade stack, a post carried by said plate and extending thru said openings, means to support said plate at positions thereon remote from said post to permit said plate to be flexed to a position in which it will urge said post upwardly, and cooperating means on said post and said slider for depressing said post when said slider is moved rearwardly and for holding said post depressed while said slider is in a rearward position, said post comprising portions of said plate cut away from an interior portion of the plate.
